DESIGN FOR A CONTAINER CAP

Joel Kronman, Whitestone, N. Y., assignor to Victor Industries Corporation, a corporation of
New York

Application September 18, 1947, Serial No. 141,466

Term of patent 14 years

(Cl. D58—26)

To all whom it may concern:

Be it known that I, Joel Kronman, a citizen of the United States and resident of Whitestone, county of Queens, city and State of New York, have invented a new, original, and ornamental Design for a Container Cap, of which the following is a specification, reference being had to the accompanying drawing, forming a part thereof, wherein:

Fig. 1 is a top plan view of a container cap, showing my new design.

Fig. 2 is a side elevational view thereof.

Fig. 3 is a fragmentary vertical sectional view thereof showing particularly, the details of the top and bevelled corner of the cap.

I claim:

The ornamental design for a container cap, substantially as shown and described.

JOEL KRONMAN.
